ADAM H. PRENZEL, OF HALIFAX, PENNSYLVANIA, ASSIGNOR TO UNITED SHOE MACHINERY CORPORATION, OF PATERSON, NEW JERSEY, A CORPORATION OF NEW JERSEY

METHOD OF AND MACHINE FOR NAILING HEELS

Application filed July 12, 1927. Serial No. 205,151.

This invention relates to a method of and machine for driving nails into the heels of boots and shoes and more particularly to nail inserting mechanism having especial advantages when used to attach rubber heels.

As the employment of rubber heels in the original factory production of shoes becomes more and more prevalent, the need for an efficient nailing machine for rubber heels which is not subject to the disadvantages and productive of the waste of material attendant upon the operation of such machines as are now used, becomes increasingly apparent.

As manufactured rubber heels have their tread faces formed with bosses encircling nailing holes axially aligned with washers which are embedded in the body of the heel substantially above the tread face and providing an ornamental appearance for the heel while also forming suction cups to prevent or reduce slipping. The patterns in which these bosses and holes are arranged vary, not only as to spacing but as to arrangement with different makes and sizes of heels.

The nailing machines as now employed or proposed for attaching rubber heels to shoes are subject to the following disadvantages; gang drivers operating through pattern plates (a series of which are quite expensive) cannot adapt themselves to manufacturing inequalities of depth and relative locations of the washers with misalignment resulting in ruined rubber heels and possible damage to the driver; as heretofore practised, no allowance has been made for the resilience of the compressed rubber of the heel in the driving of the nail with the consequence that the nails are driven to bring their heads against the washers and are either pulled loose by the back spring of the rubber after driving pressure is removed, or result at such points in distorting the edge of the heel and harmfully affecting the appearance of the finished job; no adequate guiding means has been provided for the nails so that they sometimes are driven in at an angle and fail to clinch; and where the washers are located close to the edge of the heel the method of inserting nails and the applying mechanism now used frequently, through inadequate guiding, drives

the nail through the side of the upper adjacent to the heel edge thereby marring the upper.

The method of nailing rubber heels to shoes in a manner to cure these defects and objections and an advantageous form of nailing mechanism with the aid of which the method may be practised and which embodies novel structure to that end are discussed and explained in detail in the following specification reference being had to the accompanying drawings forming part thereof and in which:

Figure 1 represents a well known type of nailing machine of the single reciprocating driver type to which the mechanical improvements of the present invention may advantageously be applied in exemplifying the inventive method and mechanical features involved therein.

Figure 2 is a detail in front elevation of the race way, driving nozzle and heel gauge with a supported shoe having its heel positioned and adjusted to the gauge, parts being shown in section.

Figure 3 is a similar view, but with the shoe support moved to insert the driver nozzle in a washer opening in the rubber heel of the supported shoe and to apply compression to the rubber heel through the washer.

Figure 4 is a plan view of the adjustable shoe support.

Figure 5 is a detail of the support showing the shock absorbing and compression applying spring of the shoe support.

35 In the method of attaching rubber heels to shoes involved herein, advantage is taken of the cup shaped suction holes and bosses, which both ornament and form anti-slip treads for the heel surface and which in the manufacturing of rubber heels are axially aligned with the metal fastener retaining washers which are imbedded in the material of the heel in process of manufacture. A nail guiding and driving instrumentality is engaged with one of these imbedded washers 40 upon a heel mounted for attachment upon a shoe, the latter of course being mounted upon a suitable support, and pressure is applied in a direction to cause compression of the rubber material of the heel between the washers and what I may term the shoe face of the rubber heel. While this pressure is being applied a nail or similar headed fastening is driven through the central aperture of the washer and into the material of the shoe 45 where its end is suitably clinched as by the metal heel plate of the last, but with the head of the nail arrested before reaching the imbedded washer and therefore spaced from the washer. Upon the removal of the compression against the rubber material after 50 the nail has been driven as described, the resiliency of the compressed material results in natural expansion, which will move the metal washer back toward the head of the nail to take up the space between the washer

and nail. Such a method of attaching the rubber heel therefore, prevents spoiling the rubber heels on shoes through driving the nail through the washers initially or through the back spring of the rubber distorting the 70 rubber at the edge of the heel and spoiling the appearance of the finished job at that point, as previously stated. The described operation may be performed upon successive washers of the heel or gang instrumentalities 75 may be employed.

In many rubber heels the washers and washer holes are located close to the edge of the heel and the ordinary method of straight driving of the fastener frequently, when the 80 fastening nail is not properly guided causes the nail to turn off at an angle to the outside edge of the shoe and to penetrate and scar the bottom edge of the upper adjacent to the line of the heel. My improved method of 85 fastening prevents this, and consists in holding the heel on the shoe under pressure and in driving the nail through the rubber heel at its edge and through the opening of the washers with the nail and heel relatively 90 inclined toward the median line of the shoe. The performance of this method by appropriate instrumentalities is illustrated in Figure 14 of the drawings. Advantageously, in performing this operation, the imbedded 95 metal washer may be and preferably is subjected to rubber compressing pressure and the head of the nail spaced from the washer as heretofore described.

The compression of the rubber material of 100 the heel between the washer and its shoe face is illustrated in Figure 3 of the drawings; and on an enlarged scale in Figure 7, in which the nail is shown as driven the appropriate distance and clinched with its head spaced 105 from the imbedded washer. Figure 8 illustrates this heel with the pressure removed and the driving instrumentalities withdrawn, showing the manner in which the compressed heel material will spring the washer back toward the head of the nail. 110

In devising mechanical instrumentalities for carrying out the hereinbefore described method, I have selected as a basis, a well known type of nailing machine of the single 115 reciprocating driving plunger, fixed stroke type and have provided means, which in co-operation with such a machine is effective to efficiently practice the described process and which in themselves are productive of novel 120 mechanical functions and structure herein related and claimed.

In Figure 1 of the appended drawings, such a machine is shown and comprises the standard 1 uprising from a suitable base 2 125 and having an operating head 3 at the rear of which is supported an operating shaft 4 driven by a belt from a base pulley 5 which receives motion by a belt connection from a suitable over-head line or power shaft. 130

Motion is communicated to the operating shaft 4 from the power receiving pulley 5 by means of a treadle operated pawl 6 controlling a suitable clutch. The head 3 at its forward end provides a plunger barrel 7 and offset therefrom laterally. A nail race-way 8 inclining upwardly to a nail hopper 9 having the usual rotating distributing drum 10, pulley driven from the power shaft 4, is connected at its lower end with a nozzle member of novel construction and arrangement having a central nail passage therein of a diameter to engage and guide the heads of the nails used, said passage being aligned axially with the driver 11 connected to and operated by the power driven plunger guided in the barrel 7 for vertical reciprocation and actuated by cam and lever from the power shaft 4, this plunger and driver having a fixed stroke, predetermined by the formation of the cam.

The nail guiding and driving nozzle, previously referred to which is designated generically by the numeral 12 is threaded into the base of the race-way 8 in co-axial alignment with the nail driver 11, the nails in the race-way being fed in a vertical plane which will bring them at the lower extremity of the end set in line with the driver and the central aperture in the nozzle 12. In the well known type of nailing machine herein shown, a thin spacer plate 13 (Fig. 6) reciprocated through a head guided slide 14 and cam and link connections with the power shaft 4, is operated in timed relation to the movement of the plunger and driver to feed said nails singly to the nozzle. In the machine shown, the driver 11 is held at the lower extremity of its stroke at the end of the operation, the spacer plate 13 being at that time inserted between the two lower-most nails in the race-way chute so that as the plunger moves upwardly at the movement of the next clutch initiated operation of the machine and rises above the end of the race-way, the lower-most nail is fed into the central nail guide opening of the nozzle 12. The last mounted shoe to which the rubber heel is to be applied is supported for vertical movement toward and from the nozzle 12 upon a table 15 engaging the upper end of a rod 16, which in turn is guided in brackets attached to the standard for vertical reciprocating movement which is effected through a lever 17 connected at one end to the rod 16 and at its other end by a cam operated link 18 to the power shaft 4, the intermediate portion of the lever being pivotally mounted upon a standard carried bracket 19. The treadle for operating the clutch controlling pawl is indicated at 20, Figure 1.

The work table 15 is formed with a radial extension 21 from which upstands a pivot bolt 22 embraced by the walls of an elongated slot 23 formed in a narrow arm 24 extended

from a work shifting and carrying plate 25 and equi-distant stop lugs 21a. This plate is provided with a suitable manipulating handle 26 by means of which it may be swung to pivot on the bolt 22 or may be moved lengthwise in the slot 23 relatively to the bolt to position the heel of a carried last and shoe in the proper relation to the operating mechanism of the machine. The last is mounted upon a heel pin or last spindle 26 of usual construction held by a suitable set screw in a socket formed in a cylindrical standard 27 having an intermediate knurled adjusting ring 28 and reduced in diameter at 29 at its lower end and threaded for vertical adjustment in the correspondingly threaded central bore of a block 30. This block is guided for vertical movement upon pins 31 upstanding from the work carrying plate 25 and is moved upwardly manually to clamp the heel 25 against the nail nozzle and to apply rubber compressing pressure thereto. This is effected manually by the machine operator through means now to be described and in order to absorb the nail driving shock of the machine and relieve the operator, the connection between the manually operated means and the supported work table includes a spring or resilient member. Accordingly, the block 30 is provided with a socket 32 therein at one edge extending downwardly from the top and terminating adjacent to the bottom of the block. The hooked pin 33 having an abutment washer 34 thereon in line with the socket 32 is secured to the block 30 rigidly and an operating handle 35 is pivoted between spaced ears 36 upstanding from the work supporting table 25 by means of a relatively long pivot pin 37, the projecting ends of which outside of the ears are encircled by the oppositely coiled ends of a spring yoke 38 extending beneath the operating handle and normally holding it in inoperative pressure applying position. This pressure is effected by means of a foot extension 39 of the operating lever seating in the base of the socket 32 and engaging the lower end of a coil spring 40 housed in the socket 32 between the abutment washer 34 and said foot extension. Obviously, by depressing the lever 35, the spring 40 is placed under pressure and through the hook 33 will lift the block 30 and with it the standard 27 of the heel pin. The work table 15 is dropped with the shoe at the end of the nail driving operation to permit the removal of the last with its shoe and as in the present case, where the nail operation is performed upon successive portions of the heel, to permit the last to be swung and adjusted into position for the next nail driving operation. In positioning the heel on the last-carried shoe on the spindle 26, the work table is moved properly to aline the heel of the shoe, and to this point, it should be stated that rubber heels whether

alone or cemented upon leather lifts or bases are mounted upon the heel end of the shoe and appropriately cemented thereto as a preliminary to the heel nailing operation involved herein. The heel thus cemented to the shoe and mounted upon the last pin 26 is brought beneath a positioning stop in the form of a flat foot 41 of a guide plate 42 mounted in predetermined adjustment on the side of the nail race-way 8 and depending therefrom, the plane of the base of the foot 41 being adjusted to the plane of the upper tread face of the heel when next moved into cooperative relation and engagement with the nozzle 12. To effect this preliminary positioning adjustment of the heel, the knurled ring 28 of the standard of the last pin is operated to bring the tread of the heel against the foot. In this position, the block 30 is resting upon the work carrying plate 25. The latter is now swung through its handle 26 to bring a washer opening with its ornamental encircling boss and imbedded washer in line with the nail driving opening of the nozzle 12, the lower end of which is formed as a conical nose sized to enter in the washer opening and engage the washer. The construction and adjustment features of this nozzle and its associated parts forms an important feature of the present invention and its functions are essential to the carrying out of the nailing method involved.

The nozzle 12 at its upper end is formed with an externally threaded tube 43, which screws into a threaded socket in the base of the race-way 8 in axial alignment with the nail driver 11 and with the line of nail feed, having a central bore 44 substantially coincident in diameter with that of the driver 11 and of the nail to be used and down which the nails are fed by gravity in advance of the driver 11. The upper end of the tube 43 is preferably formed as a rounded concavity to facilitate the feeding of the nails. The lower end of the sleeve 43 enters a socket 45 internally threaded for engagement therewith and located in the upper end of the body of the nozzle which, as will be seen from Figures 7 and 15, is of flat tapering form with an annular enlargement 46 at its base, reduced in diameter and externally threaded to provide an externally threaded sleeve 47 engaged by the internally threaded positioning ring 49 adjustable thereon vertically by means of the threads and arranged to have its lower edge inclosing the boss or rim about the tread face of the heel with which the nail driving openings and imbedded washer apertures are in axial alignment. The manipulation of the adjusting ring 49 will relatively position the conical end of the nozzle vertically. Such an adjustment is necessary to compensate for variations in the distance of the washer from the tread face of the heel. Ordinarily one

adjustment is sufficient for a "run" of heels of similar manufacture.

In driving a nail through an imbedded washer, it is essential that the nail be driven straight in order that it may be properly clinched and as a prerequisite to straight driving, straight guiding is necessary. In the nozzle construction involved in the present invention, adequate provision is made to secure proper guidance of the nails by providing a nail holding and guiding surface which extends below the point at which the head of the nail is driven. In the illustrated embodiment of my invention, this result is attained by forming at diametrically opposed points slotted openings 50 in the base of the nozzle and internally of the enlargement 46, this recess receiving guiding lugs 51 attached to and depending from the lower end of spring fingers 52 which are attached by suitable screws to the side faces of the nozzle adjacent the tube thereof, the lugs 51 extending through the recesses and having their inner faces 53 concaved to correspond substantially to the curvature of the nail and driver. The exteriorly curved and tapered bases 54 of these nail guides form the conical lower end of the nozzle which projects into the nail slot and abuts the imbedded washer. The spring 52 carrying the nail guides will yield outwardly as the nail is driven, but at no time during the driving of the nail will they be out of contact with the head of the nail, as the diameter of driver and nail, and nozzle bore and nail guide jaws 51 coincide, so that nails will be guided for straight line movement by the engagement of its head with the wall of the central recess 55 of the main body of the nozzle whose diameter corresponds to that of the nail heads and driver 11 and as the nail enters through the central aperture of the washer, its head engages the curved guiding walls 53 of the guide blocks 51 and spring them outwardly, but being held in engagement therewith by the tension of the spring fingers 52. This movement of the guide blocks outwardly is permitted by opposed slots 56 formed in the enlargement 46 at opposite sides of the nozzle body as best seen in Figures 9 and 15.

Adjustment of the nozzle body 12 vertically and in a line longitudinally to the axis of the driver, and relatively to the driver to vary the extent to which the nail is driven by the driver into the shoe, is effected through adjustment of the nozzle on the threaded sleeve 43. Because of the necessity of aligning the upper end of this sleeve with the base of the nail race-way, the position of the sleeve in the base of the race-way is fixed, as for instance by a pin or set screw 57 shown in dotted lines in Figure 7 and carried by the lower end of the race-way. The nozzle 12 therefore is turned relatively to the sleeve 43 and thereby raised or lowered with its central

nail and driver bore 55 in alignment with the similar bore 44 of the sleeve. A lock nut 58 is utilized as a stop and carries as a unitary part of itself, a circular plate 59, whose edge will be positioned closely adjacent to the vertically extending face of a scale plate 60 secured to and depending from the lower end of the race-way and having a calibrated scale with which the plate 59 cooperates as an indicator and by means of which, the stroke adjustments of the nozzle may be definitely predetermined. The nut 58, therefore is moved independently of the nozzle to the point on the calibrator scale plate 60, indicating the adjustment required for a particular run of heels, after which it is fixed in position on the sleeve by a lock nut 61 and the body of the nozzle 12 is thereafter rotated and brought into engagement with the undersurface with the stop formed by the underfaces of the nut 58 and plate 59.

In adjusting the nozzle for any series of nailing operations involving, for example, the use of rubber heels of the same manufacture which will uniformly gauge for thickness, the requisite nail driving stroke of the plunger is provided for by the adjustment of the nut 58 and plate 59 relatively to the stroke plate 60 and the nozzle is adjusted accordingly. Ordinarily, also the initial adjustment of the tread engaging ring 49 is sufficient to position the conical lower end of the nozzle for proper cooperation with the washer of any given run of rubber heels, any slight or minute variations in the locations of the washers, vertically of the heel being compensated for in the application of pressure to the heel through the spring 40 of the last support. This spring, additionally, is a safeguard against crushing of the washer through improper adjustment of the nozzle. Such an improper adjustment, is however, most unlikely with the safety factors afforded by the positioning stop 42 which effects a preliminary adjustment of the tread surface of the heel in the plane of the lower edge of tread engaging ring 49 of the nozzle, the calibrated adjustment of the extent to which the nail is driven beyond the washer, and the fact that the annular stop shoulder 48 at the base of the nozzle and forming a unitary and rigid part thereof will prevent the projection of the conical end of the nozzle into the nail driving openings in the heel tread beyond the maximum predetermined by the minimum over-all height of the adjusting ring 49 and enlargement 46 in the position shown in Figure 7 of the drawings.

From the foregoing, it will be evident that the operation of the described mechanism, in inserting fastening or nails in rubber heels in accordance with the method involved herein is as follows:

The proper adjustments for the driving stroke of the nail by adjustment of the last

relatively to stop 42 and through the nozzle adjustment just described having been made and the last on its support having been swung to position a nail opening in the heel in line with the lower end of the nozzle, the handle 35 is depressed, lifting the last vertically and forcing the conical lower end of the nozzle member into the nail opening and against the washer and compressing the material between the washer and the shoe face of the rubber heel. As this compression is effected, the operator through treadle 20 trips the pawl 6 and permits the usual one cycle clutch of the machine to operate. As the operating shaft 4 begins to turn, the driver 11 is lifted, permitting a nail to drop down into the adjusting sleeve bore 44, thence through the guiding bore 55 of the main body of the nozzle and between the bottom jaws 53, the driver 11 engaging the head and urging it through the jaws and with its point penetrating through the lower portion of the rubber heel, the heel base or lift and against the metal plate upon the heel of the last by means of which it is clinched. The movement of the driver is arrested before the head of the nail reaches the washer as indicated in Figure 7. The preliminary adjustments based on the size of nail used and thickness of heel has predetermined this result. The nail head, being guided between the spring pressed jaws 53 whose contour coincides with that of the edge of the nail head, is maintained in a vertical position during the driving operation and penetration through the rubber heel lift and upper in a straight line is assured. This operation takes place almost instantaneously and the shoe support 15, lever 17, and cam operated link 18 are thereupon actuated to drop the support, permitting the operator to swing the shoe carrying plate 25 to one side for the next height gauging operation and for the positioning of a fresh nail opening for nail insertion. Almost immediately after the shoe support 15 is dropped, it is again raised through the cam into position for the next operation. I find it is more advantageous to nail the heel by successive single nail insertions, rather than by the use of gang nailer. One advantage is the greater saving effected through dispensing with the use of expensive series of pattern templates and the use of heavier and more expensive gang nailing equipment. In addition to the saving effected through lower investment, the new method and mechanism overcomes heel spoilage. The time saved by the gang operation is offset by the time lost in selecting the pattern and aligning it, this advantage being overcome by the speed of successive nailing operations with the lighter machine and the lack of heel spoilage.

In operating upon rubber heels where the washer and nail holes are close to the edge, it is highly desirable to avoid driving a nail

through the heel into the outer face of the upper at the bottom edge adjoining the upper edge of the heel. This is particularly so in the case of the broad heels and extension heels used in many of the "sport" type 5 shoes. To overcome this and in accordance with the practice of the method forming the subject matter hereof, I employ what may be termed an angling ring or gauge 62 internally threaded and corresponding to the 10 tread engaging ring 47, except that the lower tread engaging edge is formed with an incline 63, best seen in Figures 14 and 16 of the drawings. In operating upon such heels, the shoe is inclined upon the last pin as indicated in Figure 14 and the inclined edge 63 of the tread ring swung to a corresponding incline. When pressure is applied as previously described, the nail will be driven 15 through the opening of the washer and through the shoe at an angle in which the point of the nail inclines toward the median line of the shoe and away from its edge, thereby avoiding projecting into and injuring the lower edge of the upper at the heel. 20 In Figures 17-19 a modified form of nozzle is shown, in which instead of the tapering flat body shown in Figure 15, a tubular body 64 is similarly formed with a central bore 65 is used, this body having adjacent to its upper 25 end an annular enlargement 66 providing a stop engaging the base of the race-way 8 and positioning the upper end of the tube in proper relation to the race-way. Adjustment 30 to vary the projection of the nail beyond the end of the nozzle through the fixed stroke of the driver is provided for by a sleeve 67 engaging the lower threaded end of the tubular nozzle 64 and having an annularly enlarged base providing a tread engaging flange 35 68 corresponding to the lower edge of the rings of the tread engaging ring or band 49. The lower end 69 of the nozzle 64 as shown, is tapered, projecting below the foot 68 and 40 into the nailing hole of the rubber heel, the extent of the projection being predetermined by the adjustment of the sleeve 67 thereon. When operating upon rubber heels in which 45 the nail holes are positioned close to the edge of the heel, the sleeve member 70 with its inclined or beveled foot 71 as shown in Figure 18 is substituted for the sleeve 67, the operation being the same as that of the first form of inclined tread engaging sleeve or ring 62 50 just described.

The method and means disclosed herein have been given specific and detailed disclosure and embodiment to exemplify the invention. I wish it to be understood however, 55 that variations both in the method involved and the mechanism provided are to be considered as part of the invention, so long as they remain within the spirit thereof and are within the scope of the appended claims. It 60 will be obvious also that while the invention

is described as adapted to nail rubber or elastic heels, the same conditions may exist with reference to similarly formed cushioning surfaces, such for example as rubber soles, and the term elastic or rubber heel is therefore to be construed in a descriptive and not in a restrictive sense, unless otherwise required by the prior art. 70

Having described my invention what I claim and desire to secure by Letters Patent is:

1. The method of nailing elastic heels having imbedded washers to shoes which consists in holding the heel on the shoe under compression and driving a nail through an imbedded heel washer and into the material of the shoe and arresting such movement of the nail with its head spaced from the washer and thereafter relieving compression of the heel and permitting the compressed material to move the washer relatively to and toward the head of the inserted nail. 80

2. The method of nailing elastic heels having imbedded washers to shoes which consists in holding the heel on the shoe under pressure including pressure applied to an imbedded washer, driving a nail through the opening of said washer and into the material of the shoe, arresting such movement of the nail with its head determinately spaced from the washer, and thereafter relieving pressure against the washer. 90

3. The method of nailing elastic heels to shoes at the edges of the heel which consists in holding the heel on the shoe and guiding a nail into and driving it through the edge portion of the rubber heel into the shoe with the nail and heel relatively inclined to insert the nail at an angle inclining toward the median line of the shoe. 100

4. The method of nailing elastic heels having imbedded washers at the edges of the heel which consists in holding the heel on the shoe under compression and driving a nail through an imbedded edge washer with the nail and heel relatively inclined to insert the nail at an angle directed toward the median line of the shoe and arresting movement of the nail with its head spaced from the washer and thereafter relieving compression of the heel. 110

5. The method of nailing elastic heels having imbedded washers therein to shoes which consists in holding the individual nail and washer holes in the tread of the heel successively in cooperative relation to a single acting nailing means, applying rubber compressing pressure to the heel through a washer at the point of the nail insertion, driving a headed nail through each nail and washer opening with the nail arrested with its head spaced from the imbedded washer and relieving pressure upon the heel and washer after the nails have been so driven to permit the compressed rubber to move the washer back toward the nail head. 120 125 130

6. Means for attaching elastic heels containing washers comprising heel engaging instrumentalities constructed and arranged to compress the elastic material of the heel 5 between a washer and the shoe and cooperating nail driving instrumentalities constructed and arranged to drive a nail through said washer and the heel while so compressed and to arrest driving movement with the nail 10 head spaced from the washer.
7. Means for attaching elastic heels containing cavities in their tread faces comprising instrumentalities constructed to engage the heel below a cavity to compress the 15 elastic material below said cavity, and arranged to drive a headed nail in through the heel at the bottom of the cavity, while so compressed and to arrest said nail with its head spaced from the compressed base of 20 said cavity.
8. Means for attaching elastic heels containing washers and cavities in their tread faces in register with the washers comprising instrumentalities constructed to compress 25 the elastic material below said washers and nailing mechanism constructed to drive headed nails through said washers and heel with the heel under compression and arranged to arrest said nails with their heads 30 predeterminedly spaced from said washers.
9. Means for attaching elastic heels containing cavities in their tread faces comprising a shoe support and cooperating nailing mechanism providing nail guiding means 35 formed to enter into said cavities and engage the bases thereof, means for effecting relative movement of the shoe support and nail guide to compress the elastic material therebetween said nailing mechanism being constructed 40 and arranged to drive a headed nail through said guide and heel with the latter under compression and to arrest the nail with its head spaced from the base of said cavity.
10. A nailing machine having in combination, a work support, a cooperatively positioned reciprocating nail driver having a fixed driving stroke, nail feeding means including a nail guiding nozzle alined with and below the driver and in which the driver reciprocates and a positioning gage therefor 45 adapted to engage the tread face of the work, and means for adjusting said nozzle longitudinally of its axis and that of the driver variably to regulate the driver effected projection of nails from said nozzle.
11. A nailing machine for elastic heels having nail securing cavities in their tread faces comprising in combination, a shoe support, a cooperatively positioned reciprocating nail driver having a fixed driving stroke, nail feeding means including a nail guiding nozzle alined with and receiving the driver and nails having its extremity tapered to enter said tread cavities and having a stop 60 member adjacent thereto to engage the tread 65 of the shoe and determinately to position the nozzle extremity in said cavities.
12. A nailing machine for elastic heels having nail securing cavities in their tread faces comprising in combination, a shoe support, a cooperatively positioned reciprocating nail driver having a fixed driving stroke, nail feeding means including a nail guiding nozzle alined with and receiving the driver and nails having its extremity tapered to 70 enter said tread cavities, and having a positioning gage adjacent thereto constructed and arranged to engage the tread face of the work and determinately to position the nozzle extremity in said tread cavities as to depth and angle of nail insertion relatively to the tread face.
13. In a nailing machine for elastic heels having nail receiving cavities in their tread faces, a nail guiding nozzle presenting an extremity tapered to enter in said tread cavities and having a tread engaging stop member adjustably mounted thereon variably to predetermine the extent of projection of the nozzle extremity into said cavities, said stop member having its tread engaging face constructed and arranged to cooperate with said tread to determine the angle of nail insertion relatively to the plane of the tread face.
14. A machine for nailing elastic heels having nail receiving cavities in their tread faces comprising an operating head, a reciprocating nail driver carried thereby and having a stroke of fixed length, nail feeding mechanism including a heel engaging nail-guiding nozzle alined with said driver and having its extremity formed determinately to project into said cavities, a shoe support on which a last is mounted for movement transversely of and also toward and from said nozzle, means for moving the supported last and shoe to engage said nozzle extremity in a heel tread cavity under yielding pressure, and means for determinately adjusting said nozzle longitudinally relatively to the stroke of said driver to vary the extent of driver-effected projection of the nail from said nozzle extremity.
15. A machine for nailing elastic heels having nail receiving cavities in their tread faces comprising an operating head, a reciprocating nail driver carried thereby having a driving stroke of fixed length, nail feeding mechanism including a heel-engaging nail guiding nozzle alined with said driver and having its extremity formed to project into said tread cavities and having means predetermining the extent of such projection, a heel positioning gage in determinate relation to the plane of the nozzle, a shoe support on which a last is mounted for movement transversely of and toward and from said nozzle including a last pin mounted manually adjustable toward and from said heel position-

- ing gage, means for raising the supported last and shoe to engage said nozzle extremity in the heel tread cavities under yielding pressure effective to compress the elastic material of the heel, means for driving nails through said cavities into the heel while the latter is held so compressed, said nozzle being constructed and arranged for longitudinal adjustment relatively to the driver stroke variably to predetermine the extent to which the nail is driven through the heel.
16. In a nailing machine, nailing mechanism including a driver, nail feeding mechanism including a nail guiding nozzle alined with the driver and adapted to engage the work, and a work support mounted for movement toward and from said nozzle and having a last spindle mount mounted thereon for independent movement toward and from said nozzle, and means for effecting movement thereof toward said nozzle comprising a pivotally mounted operating lever and a compressible spring interposed between said lever and the last spindle mount.
17. In a nailing machine, nailing mechanism including a reciprocating driver having a fixed driving stroke, nail feeding mechanism including a nail-guiding work engaging nozzle alined with said driver, a support upon which said nozzle is adjustable in a direction longitudinally of the driver stroke variably to predetermine the extent of driver-affected projection of the nails from said nozzle, a seated gauge plate adjacent to said nozzle and in cooperating adjustment, an indicator mounted on said nozzle support independently of the nozzle and acting as an adjustment stop therefor, and means for locking said indicator in adjusted position.
